US00D984519S

(12) **United States Design Patent** (10) **Patent No.:** **US D984,519 S**
Chu (45) **Date of Patent:** **** Apr. 25, 2023**

(54) **CLAMP BASE FOR MONITOR ARM**

(71) Applicant: **Eastern Global Corporation**, New Taipei (TW)

(72) Inventor: **Leo Chu**, New Taipei (TW)

(73) Assignee: **Eastern Global Corporation**, New Taipei (TW)

(**) Term: **15 Years**

(21) Appl. No.: **29/738,422**

(22) Filed: **Jun. 17, 2020**

(51) **LOC (14) Cl.** **16-05**

(52) **U.S. Cl.**

USPC **D16/241**

(57) **CLAIM**

The ornamental design for clamp base for monitor arm, as shown and described.

DESCRIPTION

FIG. 1 is a perspective view of a clamp base for monitor arm showing my new design;

FIG. 2 is a front elevational view thereof;

FIG. 3 is a rear elevational view thereof;

FIG. 4 is a top plan view thereof;

FIG. 5 is a bottom plan view thereof

FIG. 6 is a left side elevational view thereof;

FIG. 7 is a right side elevational view thereof;

FIG. 8 is a perspective view from other side;

FIG. 9 is another perspective view of the clamp base for monitor arm shown in state of use; and,

FIG. 10 is an alternate perspective view of the clamp base for the monitor arm shown in a state of use thereof.

The broken lines in the figures depict portions of the clamp base for monitor arm and form no part of the claimed design.

The broken lines in FIG. 9 and FIG. 10 represent environment that forms no part of the claimed design.

1 Claim, 10 Drawing Sheets
